UNITED STATES PATENT OFFICE.

RICHARD J. GREENWAY, OF WESTERLY, RHODE ISLAND, ASSIGNOR TO C. B. COTTRELL & SONS COMPANY, OF STONINGTON, CONNECTICUT, A CORPORATION OF DELAWARE.

ANTIOFFSET MECHANISM FOR PRINTING PRESSES.

Application filed March 3, 1925. Serial No. 12,847.

The object of my invention is to provide certain improvements in the construction, form and arrangement of the several parts of the offset mechanism whereby antioffset powder is applied to the surface of a movable offset element, such as the offset cylinder which comes in contact with a freshly printed side of a traveling web, so as to not only prevent smutting or sticking of the sheets in the delivery pile but also to prevent offsetting onto the packing of the offset cylinder, thereby materially prolonging the effective life of the said packing.

A practical embodiment of my invention is represented in the accompanying drawings, in which—

Fig. 1 represents in side elevation so much of a web perfecting printing press as includes my improved anti-offset mechanism.

Fig. 2 represents a longitudinal vertical section through the same.

The web 1 which has just been printed upon one side by the first printing unit (not shown herein) is represented as passing around the offset cylinder 2 of the second printing unit to be printed on its opposite side. This offset cylinder 2 has its shaft 3 suitably mounted in the frame 4.

The offset cylinder 2 may be provided with the usual packing 5. The endless belt 6 passes around the drive roll 7, the idler rolls 8, 9 and the belt tightener roll 10. These rolls are all suitably mounted in the frame 4 and the rolls 8 and 9 are so arranged as to cause the endless belt 6 to have an extended contact with the packing 5 on the offset cylinder 2.

The anti-offset powder supply fountain is denoted by 11 and its fountain roll 12 is arranged in position to supply the anti-offset powder directly to the endless belt 6 for transfer thereby onto the packing 5 of the offset cylinder 2.

An adjustable doctor knife 13 is mounted in the fountain 11 in position to regulate the amount of anti-offset powder supplied by the fountain roll 12 to the endless belt 6.

The offset cylinder, the endless belt and the fountain roll are driven at the same surface speed through the gears 14, 15, shaft

16, bevel gears 17, 18, shaft 19, bevel gears 20, 21, shaft 22 and gears 23, 24.

It will be seen that by this arrangement I am enabled to apply the anti-offset powder to the surface of the offset cylinder 2, which comes in contact with the freshly printed side of the traveling web 1, the supply being regulated by the doctor knife 13, so that all waste of the powder may be eliminated and also so that too much powder need not be applied to the freshly printed side of the web. This arrangement not only increases the effective life of the packing on the offset cylinder by preventing offset thereon, but also prevents the smutting and sticking of the sheets cut from the web when delivered into the pile.

It is evident that various changes may be resorted to in the construction, form and arrangement of the several parts without departing from the spirit and scope of my invention; hence, I do not intend to limit myself to the particular embodiment herein shown and described, but

What I claim is:—

1. A rotary offset cylinder around which a traveling web is passed with a freshly printed side in contact therewith, a traveling endless belt arranged for contact with said cylinder, an anti-offset powder supply fountain, and a fountain roll for supplying anti-offset powder to the said belt for application thereby to the web contacting surface of the offset cylinder.

2. A rotary offset cylinder around which a traveling web is passed with a freshly printed side in contact therewith, a traveling endless belt arranged for contact with said cylinder, an anti-offset powder supply fountain, a fountain roll for supplying anti-offset powder to the said belt for application thereby to the web contacting surface of the offset cylinder, and means for driving the cylinder, belt and fountain roll at the same surface speed.

In testimony, that I claim the foregoing as my invention, I have signed my name this 27th day of February, A. D. 1925.

RICHARD J. GREENWAY.
